UNITED STATES PATENT OFFICE.

VICTOR R. DESPARD, OF VALPARAISO, INDIANA, ASSIGNOR TO MCGILL MANUFACTURING COMPANY, OF VALPARAISO, INDIANA, A CORPORATION OF INDIANA.

INSULATED MOUNTING FOR ELECTRICAL CONTACTS.

Application filed July 19, 1924. Serial No. 727,042.

My invention relates to a mounting for electrical contacts and more particularly to an insulating mounting for electrical contacts.

It is a purpose of my invention to provide means for mechanically fastening metallic parts of electrical wiring devices or other electrical contacts to their insulating bases or supporting means so as to positively position and fasten the same relative to the insulating base member.

In the methods now in use, the contacts or wiring terminals are usually provided with a foot that lies flat against an insulating surface and are held in place by a screw that extends through a counter-sunk hole in the insulating material, the head of the screw being encased in an insulating compound to prevent the screw from working loose. This method of assembling the parts is slow and comparatively expensive and furthermore, does not assure that the terminal will be positively held in place as in spite of the use of the insulating compound about the head of the screw, the screw often works loose so as to allow movement of the metallic member carrying the terminal screw relative to the insulating supporting means.

It is a purpose of my invention to provide contact carrying members that are provided with prongs or projections that extend through openings or slots in insulating members that are preferably of some form of insulating sheet material, said projections or prongs being clinched or upset after being passed through the openings in the insulating material to firmly secure the insulating members and the metallic terminal carrying members in assembled relation. Preferably, a laminated insulating material or molded bakelite is used for the insulating members.

It is still a further purpose of the invention to provide means for securing conducting members such as contact terminal carrying members to a pair of insulating base members so that said conducting members carrying the wiring terminals are held in a definite fixed relation to the insulating members and said insulating members are held in a definite fixed position relative to each other by said conducting members which space said insulating members and secure the same together.

It is still another purpose of the invention to provide a switch member comprising a

pair of insulating members of sheet insulating material which are provided with a pair of wiring terminals that are secured to the insulating members so as to positively fix the position of said insulating and conducting members relative to each other and to provide said terminal carrying conducting members with suitable contact terminals with which a movable contact member is adapted to engage, said movable contact member of said switch mechanism being mounted on a suitable switch frame that is adapted to be held in position between said insulating members by means of said terminal carrying conducting members.

Other objects and advantages of the invention will appear as the description of the accompanying drawings proceeds. However, I desire to have it distinctly understood that I do not intend to limit myself to the exact details shown or described but that I intend to include as part of my invention all such obvious changes and modifications of parts as would occur to a person skilled in this art and as would fall within the scope of the claims.

In the drawings:

Fig. 1 is a side elevational view of a switch mechanism with the casing removed showing my improved method of securing the contact terminals to an insulating mounting;

Fig. 2 is a section of a switch mechanism with the cover in place, said section being taken substantially on a plane corresponding to the line 2-2 of Fig. 1, the cover being downward;

Fig. 3 is a top plan view of a switch mechanism with the cover removed, or as viewed from the bottom of Fig. 2, a portion thereof being broken away;

Fig. 4 is a section taken on the line 4-4 of Fig. 3; and

Fig. 5 is a view partly in elevation and partly in section showing my improved switch mechanism mounted in a canopy.

Referring in detail to the drawings, in Figs. 1 to 4 inclusive is shown a switch mechanism which is mounted on a pair of insulating members 10 and 11. Said insulating members are preferably made of some form of sheet insulating material or of thin molded insulating material such as bakelite. Preferably, said members are made of some form of laminated sheet insulating material impregnated with a phenolic condensation

product. The members 10 and 11 are provided with suitable openings 12 and 13 respectively through which the prongs or projections 14 and 15 on the plates 16 of conducting material are adapted to extend. The plates 16 are each provided with screw-threaded openings with which the terminal screws 17 are adapted to screwthreadedly engage, said screws 17 serving as wiring terminals for electrically connecting suitable conductors with the conducting plates 16, said plates or conducting members 16 being further provided with pairs of ears 18 which are located on opposite sides of the screws 17 and which extend at an oblique angle to the plates 16 and serve to confine the ends of the conductors in close proximity to the binding screws 17. In assembling these parts, the projections or prongs 14 and 15 are extended through the insulating members 10 and 11 after which the parts are placed in a press and a blow is struck endwise of the prongs or projections by said press on the parts held in the relationship referred to above, whereupon said prongs are upset or clinched as is indicated at 19 and 20 respectively to firmly secure the parts 10, 11 and 16 in a fixed position relative to each other. It is, of course, understood that the prongs or projections 14 and 15 are made of slightly greater length than the thickness of the material of the members 10 and 11 to obtain such upsetting or clinching action.

The members 16 may be made of any desired shape as long as the shape thereof does not interfere with the function thereof as means for securing the insulating members and the conducting terminal carrying members in fixed relative position, it being, of course, obvious that by clinching or riveting the parts together as described above, the members 16 are fixed in position relative to each other and to the members 10 and 11 and that the members 10 and 11 are fixed and spaced relative to each other, this spacing being, of course, accomplished due to the engagement of the members 10 and 11 with the edges or faces 21 and 22 provided on the members 16. The members 16, it will be noted from Fig. 2, are widened at the ends thereof to provide a wide bearing at the edges 21 and 22 against the members 10 and 11 and are reduced at the central portion thereof where the screws 17 engage with the same so that the ears 18 can be struck from the edge portions of the material and lie in close proximity to the screws 17. The plates 16 are provided with suitable contact members 23 with which a movable contact member 24 is adapted to engage to bridge said contacts 23. The contacts 23 are provided with ears 25 that are riveted or secured in any other suitable manner to the members 16. In the drawings the members 23 are shown as being secured by means of rivets

26 extending through suitable openings in the members 16 to said members 16, said rivets extending through aligning openings in the ears 25 on said members 23. The movable contact member 24 of the switch mechanism may be of any type, but is shown as being of an oscillating or swinging type which is pivotally mounted on suitable supports 27 on the switch frame 28 which carries an extension 29 having the universally tilttable operating member 30 provided thereon. The switch frame 27 comprises a pair of side members 31 that are provided with pairs of projections or prongs 32 that extend into the openings 33 in the members 10 and 11. Said prongs 32 are placed in the openings 33 before the projections 14 and 15 are clinched over on the members 10 and 11 and are of such length that the switch frame will be held firmly in position between the members 10 and 11 due to the engagement of the members 10 and 11 with the edge portions 34 of the members 31 when said members 14 and 15 are headed or riveted over as shown at 19 or 20.

It is, of course, obvious that if desired, the prongs 32 could also be made of a length such as to rivet the parts together thereby, but this is not necessary and is preferably not done, as the parts are more easily assembled and held together with sufficient firmness by the arrangement shown in the drawings. In view of the fact that pairs of prongs or projections are used for securing the various parts together, it is obvious that no movement of the parts relative to each other is possible, as any twisting or turning action would be prevented by the fitting of the projections in the openings in the insulating members. It is not necessary that the prongs project endwise from the plates 16 as any other shape of plate or conducting member for carrying the wiring terminals may be provided with the prongs projecting from any desired portion thereof as long as the arrangement is such as to properly space the insulating members relative to each other and secure the parts in fixed relationship. It is also obvious that while terminal screws are shown for securing the conductors to the conducting members that any form of terminals may be carried thereby such as the switch terminals 23. An opening 40 is provided in the member 10 to accommodate the contact making end of the movable contact member 24 when the same is in open circuit position. This opening is provided in order to accommodate said member so that the spacing of the contact making end thereof from the stationary contacts will be sufficiently great with the device in open circuit position. By providing this opening 40, the members 10 and 11 can be placed much closer together than would be the case if no such opening were provided and in

this way increasing the compactness of the device. This cutting away of the insulating member 10 does not affect the insulation of the entire device from the shell or other 5 current carrying parts as the insulating lining of the shell will prevent any contact of any current carrying part with the shell.

The switch mechanism described above is, of course, ordinarily mounted in a suitable 10 metallic casing 35 which is provided with a lining of insulating material 36 and in the form of switch mechanism shown, is usually mounted within the canopy 37 as shown in Fig. 5 although it is obvious that 15 the terminal carrying members mounted between the insulating members in the manner described above may form a portion of any other form of switch mechanism which may be used in any place where such switch 20 devices are usable whether in a canopy or any other position.

Having thus described my invention, what I desire to claim and secure by United States Letters Patent is:

25 1. In a device of the character described a pair of insulating members having openings therein, a pair of metallic members having projections mounted in said openings and a switch mounting engaging said 30 insulating members, said projections being upset against said members to secure said metallic members to said insulating members and to hold said insulating members in definite spaced relation to thereby hold said 35 switch mounting in position.

2. In a device of the character described a pair of insulating members, means for holding the same in fixed spaced relation to each other, a pair of contacts mounted between said insulating members and a movable contact arm pivotally mounted to swing between said insulating members into and out of engagement with said pair of contacts, one of said insulating members being 45 spaced from said contacts and having an opening therein opposite said contacts to accommodate said contact arm when the same is out of engagement with said pair of contacts and thus increase the distance 50 between the contact arm and said contacts.

3. In a switch mechanism, a pair of insulating members having openings therein, a pair of conducting members mounted between said insulating members, said conducting members each having projections entering said openings and clinched against said insulating members to hold said insulating and conducting members in definite fixed relationship to each other, and a switch frame- 55 work having projections seated in openings in said insulating member whereby said framework is held in position therebetween.

60 4. In a switch mechanism, a pair of insulating members having openings therein, a pair of conducting members mounted be- 65

tween said insulating members and extending substantially at right angles thereto, said conducting members each having a flexible contact riveted thereon and being clinched against said insulating members to 70 hold said insulating and conducting members in definite fixed relationship to each other and a switch framework having projections seated in the openings in said insulating members, whereby said framework 75 is held in position therebetween, said switch framework having a movable contact member mounted thereon adapted to bridge said contacts.

5. In a switch mechanism, a pair of insulating members having openings therein, a pair of conducting members mounted between said insulating members, said conducting members each having a switch contact thereon and having projections entering 80 said openings and clinched against said insulating members to hold said insulating and conducting members in definite fixed relationship to each other and a switch framework having projections seated in 85 said openings in said insulating member whereby said framework is held in position therebetween, said switch framework having a movable contact member mounted thereon 90 adapted to bridge said contacts. 95

6. In a switch mechanism, a pair of insulating members having openings therein, a pair of conducting members mounted between said insulating members and extending substantially at right angles thereto, 100 said conducting members each having a flexible contact riveted thereon and being clinched against said insulating members to hold said insulating and conducting members in definite fixed relationship to each other and a switch framework having pairs 105 of projections seated in the paired openings in said insulating members, whereby said framework is held in position therebetween, said switch framework having a 110 movable contact member mounted thereon adapted to bridge said contacts.

7. In a device of the character described, a pair of conducting members each having a plurality of spaced projections on each end thereof and means for holding said conducting members in definite spaced relation to each other and insulating said members from each other comprising a pair of members of insulating material each having a 120 plurality of openings therein through each of which one of said projections extends, said projections having means thereon for securing the same in said openings to form a rigid framework of said members. 125

8. In a switch mechanism, a pair of insulating members having openings therein, a pair of conducting members mounted between said insulating members and extending substantially at right angles thereto, 130

said conducting members each having a contact thereon and being clinched against said insulating members to hold said insulating and conducting members in definite fixed relationship to each other and a switch framework having projections seated in the openings in said insulating members, whereby said framework is held in position therebetween; said switch framework having a movable contact member mounted thereon adapted to bridge said contacts.

9. In a device of the character described, a pair of conducting members having projections thereon and means for holding said conducting members in definite spaced relation to each other and insulating said members from each other comprising a pair of members of insulating material having openings therein through which said projections extend, said projections having means thereon for securing the same in said openings, said insulating members and said conducting members forming a rigid rectangular framework with one pair of opposite sides of conducting material and the other pair

of sides of insulating material, and a switch frame mounted within said rectangular frame and between said insulating members, said switch frame having pairs of projections seated in paired openings in said insulating members.

10. In a device of the character described, a pair of insulating members, means for holding the same in fixed spaced relation to each other, a pair of contacts mounted between said insulating members with the contact making ends thereof lying adjacent one of said insulating members and a movable contact arm pivotally mounted to swing between said insulating members into and out of engagement with said pair of contacts, the other of said insulating members having an opening therein opposite said contacts to accommodate said contact arm when the same is out of engagement with said pair of contacts.

In witness whereof, I hereunto subscribe my name this 1 day of July, A. D. 1924.

VICTOR R. DESPARD.
